UNITED STATES PATENT OFFICE.

JOSEPH O. HARRIS, OF COLUMBIA HEIGHTS, MINNESOTA, ASSIGNOR, BY MESNE ASSIGNMENTS, TO AMERICAN BRAKE SHOE & FOUNDRY COMPANY, OF MAHWAH, NEW JERSEY, A CORPORATION OF NEW JERSEY.

MEANS FOR HOLDING INSERTS IN PLACE IN MOLDS.

1,079,550.

Specification of Letters Patent.

Patented Nov. 25, 1913.

Application filed December 17, 1912. Serial No. 737,184.

To all whom it may concern:

Be it known that I, JOSEPH O. HARRIS, a citizen of the United States, and a resident of Columbia Heights, in the county of 5 Anoka and State of Minnesota, have made and invented certain new and useful Improvements in Means for Holding Inserts in Place in Molds, of which the following is a specification.

10 My invention relates to the manufacture of cast metal articles having an insert, formed usually from wrought metal such as wrought iron or steel, embedded in them, and consists in improved means for holding 15 the insert in proper position within the mold in which the article is formed while the molten metal is being poured therein.

My invention is disclosed in connection 20 with a device for forming brake shoes, and as applied and used for the purpose of holding steel backs in place within a mold, which backs become embedded in the shoe as the same is cast, although it is equally applicable for the purpose of holding inserts to be em- 25 bedded in articles of other and various kinds.

With the purpose above mentioned in view, my invention consists in the improved means for holding inserts to be embedded in 30 cast metal articles as the latter are formed, hereinafter described and claimed, and illustrated in the drawing accompanying and forming a part of this application, and in such variations and modifications thereof 35 as will be obvious to those skilled in the art to which my invention relates; my invention being in the nature of an improvement in the means for holding inserts in place in molds patented in Letters Patent No.

40 1,016,273, Feb. 6, 1912, to Harry Jones.

In the drawings wherein the preferred embodiment of my invention is illustrated: Figure 1 is a view showing a portion of a molding machine in plan with a section of a 45 two-part flask resting thereupon and illustrating my invention as applied thereto; Fig. 2 is a view showing a section upon a vertical plane indicated by the line 2-2, Fig. 1; Fig. 3 is a view showing a detail; Fig. 4 is a view showing the upper part or cope of a sectional flask filled with sand to 50 form part of a sectional mold, a steel back being shown as secured in position, the sur-

face of the same shown being that in contact with the table of the molding machine as the section is formed; Fig. 5 is a view showing a section upon a vertical plane indicated by the line 5-5, Fig. 4; and Fig. 6 is a view showing a complete multiple part sectional mold for producing a brake shoe 60 having a steel back embedded therein, the mold being equipped with my improved means for holding the steel back for the shoe in place.

Referring to the drawings, the reference 65 numeral 7 designates the table of a molding machine, upon which the cope 8 of a sectional flask is placed, preparatory to filling the same with sand to form one part of a sectional mold in which a brake shoe or 70 other article is formed, my invention being disclosed as used in connection with a mold for producing brake shoes, although it is capable of use in other arts and in the manufacture of other devices and therefore not 75 limited in its application to the specific art referred to.

The upper surface of the table, 7 determines the contour of the lower face of the upper portion of the mold after the cope 8 has 80 been filled with sand and properly rammed, and 9, 10 are blocks supported from a reciprocating support 11, which is a part of the molding machine, the blocks being movable through openings formed in the table 85 7, said blocks being in their upper position illustrated in Fig. 2, while the cope 8 is being filled with sand, after which they are lowered preparatory to removing the upper part of the mold thus formed from the table 90 of the molding machine. The purpose of these blocks is to form recesses 12, 13 in the lower surface of the sand within the cope; and, when molten metal is poured into the mold during the process of casting, the same 95 flows into the recesses 12 and thereby provides projecting abutments upon the back of the shoe produced, and into the recess 13 to provide, in connection with a wrought metal lug carried by the insert in the specific embodiment of my invention illustrated, 100 an attaching lug by means of which the brake shoe produced may be supported from a brake head.

The reference character 14 designates one 105 or more supporting members, the number of

such members employed being obviously dependent upon the character of the insert to be supported, and which supporting members may be located at any convenient part of the flask, although as shown in the drawings they are located about mid-way of the height of the cope so as to be embedded in the sand of the mold after the cope has been filled with sand. The ends 5 of these supporting members are shown as extending through holes in the sides of the cope portion of the flask, although it will be understood that the supporting members may be supported in any suitable way.

10 The reference character 15 designates insert supporting elements embedded in the sand of the flask and which elements extend beyond the surface of the mold with which the molten metal comes into contact when the mold is used, so that the said supporting elements may engage and support an insert to be embedded in the article produced in the mold during the process of casting. These supporting elements are 15 preferably in the form of wire loops connected with or supported from the supporting member 14 above referred to, which wire being flexible, as will be understood, may be bent into engagement with the insert 20 to be supported within the mold.

25 The free ends of the wire loops 15 extend through holes 16 provided in the table 7 of the molding machine, from which it will be obvious that after the cope has been filled 30 with sand, the same properly rammed, and removed from the molding machine, the free ends of the wire will be left projecting beyond the surface of the sand in the cope which was in contact with the table 7.

35 These free ends project from the surface of the cope at the points 17, Fig. 4, located a distance apart corresponding with the width of the insert to be supported by said 40 insert supporting member or wires.

45 In the specific embodiment of my invention illustrated in the drawings I have shown a steel back 18 of a brake shoe as supported by the insert supporting elements, although it will be understood that my invention may be adapted for the purpose of holding inserts of any kind within molds 50 designed to produce any specific article of manufacture. In the embodiment of my invention illustrated, the free ends of the 55 flexible insert supporting element are located a distance apart such that the steel back 18 above referred to may be placed between them, after which the free ends of the wire are bent over the insert and twisted 60 together as shown at 19, Figs. 4 to 6. The steel back 18 will thus be supported from the insert supporting members with one of its surfaces in contact with the surfaces of the sand of the cope or other mold section, 65 although it will be understood that the in-

sert supporting member is equally well adapted for the purpose of supporting inserts at a distance from the inner surface of the mold if the article to be produced necessitates that the insert be located within, 70 as distinguished from at the surface of the article produced.

The insert 18 is provided with a centrally located wrought metal lug 20, and, as hereinbefore explained, the block 10 is provided 75 for the purpose of forming a recess in the sand of the cope into which molten metal may flow to provide, in connection with the lug 20, an attaching lug for securing the brake shoe to a brake head. To that end 80 the projection 10 is provided with end extending portions 21, Fig. 3, which form recesses for receiving the ends of a core 22 which extends through the lug 20 in the manner illustrated in Figs. 5 and 6, and also 85 with side extending portions 23 which form recesses to permit the molten metal to flow up and around the sides of the key 20. It will be understood, however, that the form of the key lug is not an essential feature of 90 my invention, and that in cases where the same is employed for the purpose of producing brake shoes the form of the block 10 will be varied to correspond with the particular form of lug with which the shoe 95 is to be provided.

Fig. 6 shows a complete multiple part sectional mold of the form or type suitable for producing a brake shoe, the same being equipped with a form of my invention suitable for holding a steel back in place within a mold, so that the same becomes embedded in the rear face of the shoe as the same is cast. The mold illustrated comprises the cope 8 above referred to, together with a 100 nowel or drag 24, the two parts inclosing a cavity 25 into which the molten metal is 105 poured as will be understood.

While I have referred to the element 8, and the sand contained therein, as forming 110 the upper part of the sectional mold in which the shoe is formed, it will be understood that this is not essential, and that the same may be so placed as to form the lower or other portion of the mold, and also that 115 the insert to be embedded in the article to be produced may be supported in any position within the mold. Also, while I have referred to the mold as formed from sand, it will be understood that this term is to 120 be understood as applying to and comprehending such materials as are commonly known and used in foundry practice for the purpose of forming molds.

In view of the premises, it will be appreciated that I avoid the use of nails or similar holding devices heretofore employed for the purpose of securing a steel back against the surface of a mold section, but which have been open to various objections, among 125

- which are that the nails are likely to pull out of the sand, as they are themselves unsupported, and that they have to be removed from the finished brake shoe before the same may be used, as by cutting them off with a cold chisel. Furthermore, the nails are likely to produce chilling, and, consequently, hard spots in the finished shoe, which results in the formation of grooves in
- 10 the car wheel with which the shoe may be used. In using wire, as contemplated in my invention, the same is for the most part oxidized and burned by the time the metal has set, and, such slight projecting pieces of
- 15 wire as may remain in the finished shoe do not require to be cut from a shoe, as they will be broken off during the tumbling process to which the shoes are ordinarily subjected for the purpose of cleaning them.
- 20 Having thus described and explained my invention, I claim and desire to secure by Letters Patent:
1. In combination, a section of a multiple part mold having a supporting member embedded therein; and an insert supporting element supported by said supporting member and embedded in said section, and which supporting element extends beyond the surface of said section with which the molten
- 25 metal contacts when the mold is used and is flexible to such a degree that its projecting portion may be bent into engagement with an insert to be supported; said supporting element being separate and distinct from
- 30 and forming no part of the insert to be supported, and the portion thereof which is embedded in said section forming no part of the article produced when said section is used.
- 40 2. The combination with a foundry flask within which a mold may be formed, of a supporting member supported from said flask; and an insert supporting element supported by said supporting member and
- 45 adapted to be embedded in sand in said flask, and which supporting element extends beyond the surface with which the molten metal contacts when the mold is used and is flexible to such a degree that its projecting
- 50 portion may be bent into engagement with an insert to be supported; said supporting element being separate and distinct from
- 55 and forming no part of the insert to be supported, and the portion thereof which is adapted to be embedded in the sand forming no part of the article produced in the use of said flask.
- 60 3. The combination with a foundry flask within which a mold may be formed, of a supporting member supported from said flask; and an insert supporting element connected with said supporting member and
- 65 adapted to be embedded in sand in said flask, and which supporting element ex-
- molten metal contacts when the mold is used and is adapted to support an insert in position to be embedded in the article formed in the mold; said supporting element being separate and distinct from and forming no 70 part of the insert to be supported, and the portion thereof which is adapted to be embedded in the sand forming no part of the article produced in the use of said flask.
4. The combination with a foundry flask 75 within which a mold may be formed, of a supporting member; and an insert supporting element in engagement with said supporting member and adapted to be embedded in sand in said flask, and which supporting element extends beyond the surface with which the molten metal contacts when the mold is used and is adapted to support an insert in position to be embedded in the article formed in the mold; said supporting element being separate and distinct from and forming no part of the insert to be supported, and the portion thereof which is adapted to be embedded in the sand forming 80 no part of the article produced in the use of 85 said flask.
5. In combination, a section of a multiple part foundry flask; a table upon which said section may rest, and which table is provided with a hole; and an insert supporting 95 element extending through the hole aforesaid in said table, and which element becomes embedded therein as the flask section is filled with sand.
6. In combination, a section of a multiple part foundry flask; a table upon which said section may rest, and which table is provided with a hole; and an insert supporting element supported from said flask section and extending through the hole aforesaid in 100 said table, and which element becomes embedded therein as the flask section is filled with sand.
7. In combination, a section of a multiple part foundry flask; a table upon which said section may rest, and which table is provided 105 with a hole; and a flexible insert supporting element supported from said flask section and extending through the hole aforesaid in said table, and which element becomes embedded therein as the flask section is filled with sand.
8. In combination, a section of a multiple part foundry flask; a table upon which said section may rest, and which table is provided 110 with two holes, and a flexible looped supporting element, the free ends of which extend through the holes aforesaid in said table, and which element becomes embedded therein as the flask section is filled with 115 sand.
9. In combination, a section of a multiple part foundry flask; a table upon which said section may rest, and which table is provided 120 with two holes; and a flexible looped in-
- 125
- 130

4
sert supporting element supported from said flask section and the free ends of which extend one through each of the holes aforesaid in said table, and which element be-
5 comes embedded therein as the flask section is filled with sand.
Signed at Minneapolis in the county of

Hennepin and State of Minnesota this 9th day of December, A. D. 1912.

JOSEPH O. HARRIS.
